No. 730,071.

PATENTED JUNE 2, 1903.

H. ACHILLES.
WASHBOILER ATTACHMENT.
APPLICATION FILED SEPT. 13, 1902.

NO MODEL.

UNITED STATES PATENT OFFICE.

HERMANN ACHILLES, OF DORTMUND, GERMANY.

WASHBOILER ATTACHMENT.

SPECIFICATION forming part of Letters Patent No. 730,071, dated June 2, 1903.

Application filed September 18, 1902. Serial No. 123,331. (No model.)

To all whom it may concern:

Be it known that I, HERMANN ACHILLES, a subject of the Emperor of Germany, residing in Dortmund, Germany, have invented new and useful Improvements in Washboiler Attachments, of which the following is a specification.

The present invention relates to a wash-boiler attachment which can be manufactured at a very low cost and which is just as effective as any similar attachment for wash-boilers on the market. Being made of wood, it offers the advantage that the linen is not spoiled by stains of rust, as is the case with metallic attachments.

The improved device forming the object of the present patent application is provided with longitudinal openings, through which the lye can circulate in the same manner as in perforated pipes, wire-nettings, and the like which have been used heretofore.

In the accompanying drawings, forming part of the present specification, Figure 1 is an elevation of the preferred form of the new device. Fig. 2 is a plan view. Figs. 3 and 4 are cross-sections of the lines 33, 44 of Figs. 1 and 5, respectively. Figs. 5 and 6 are an elevation and plan view of the device provided with a bell. Fig. 7 is an elevation of a modified form of the device, and Fig. 8 is a plan view of the same. Figs. 9 and 11 are end views of the pillar, illustrating its construction. Fig. 10 is a cross-section on line 10 10 of Fig. 7. Fig. 12 is an elevation of another modification, and Fig. 13 is the plan view thereof.

a is a pillar of wood, being traversed at its lower end by two cross-bars *b* and *b'* and having two longitudinal slots *c* *c*, crossing each other and cut clear through the wood almost the entire length of the pillar. The edges *e* may be beveled, as shown, or may remain rectangular.

The apparatus as described is placed into an ordinary washboiler, where the pillar *a* is steadied in a proximately vertical position by the bars *b* *b'*. When the linen is packed around the pillar and thrown upon the bars *b* *b'*, the water and lye which are used for boiling the linen will partly accumulate in the neighborhood of the rods *b* *b'* and will be inclosed in the slots *c*, as in a pipe, and when boiling will ascend and spread over the linen

in the same way as in boilers where metal tubes are used for this purpose. The slots 55 are so narrow that the linen cannot get in, and a channel for the rising of the boiling lye will always remain unobstructed.

Figs. 5 and 6 show a bell-shaped body *d*, secured at a slight distance above the cross-bars *b* *b'*. Such a bell prevents the linen still more efficaciously from filling the passages and leaves always a quantity of clear lye at the bottom of the boiler to ascend readily in the slots at the boiling temperature. 65

f *f* in Figs. 7 to 13 are vertical rods of wood, preferably of a square cross-section, which are connected at their bottom end by cross-bars *g* *g'*, serving the same purpose as the bars *b* *b'* in Figs. 1 and 2. The top ends of 70 the rods *f* are united by a small cross-piece of wood *i*. In Figs. 10 and 11, *h* represents wires of non-rusting metal connecting the vertical with the horizontal members for the purpose of greater stability and for the purpose of 75 keeping the linen away from the center, and thereby obtaining the same advantage as by the use of the bell *d*.

Figs. 12 and 13 represent the same device as Figs. 7 and 8. However, the wires *h* are 80 substituted by small plates *k* of metal or of wood. Besides two rings *ll* are drawn through the horizontal members, serving also the double purpose of steadyng the device and of centering a certain quantity of lye. 85

I claim—

1. An attachment for washboilers for promoting the circulation of the lye, consisting of an upright having longitudinal openings through it, and having steadyng cross-bars 90 at the foot end and means extending from the lower part of the upright to hold the clothes at a distance therefrom, substantially as described and for the purpose set forth.

2. An attachment for washboilers for promoting the circulation of the lye, consisting of an upright having longitudinal openings through it, and having at the foot end cross-bars for steadyng the upright, in combination with a bell *d* to allow of an accumulation 95 of the lye at the bottom of the boiler. 100

In testimony whereof I affix my signature.

HERMANN ACHILLES.

In presence of—

WILLIAM ESSENWEIN,
PETER LIEBER.
